UNITED STATES PATENT OFFICE.

MAURITZ C. INDAHL, OF PHILADELPHIA, PENNSYLVANIA.

INTERNAL-COMBUSTION ENGINE.

1,141,711.

Specification of Letters Patent.

Patented June 1, 1915.

Application filed May 24, 1912. Serial No. 699,396.

To all whom it may concern:

Be it known that I, MAURITZ C. INDAHL, a citizen of the United States, and resident of Philadelphia, in the county of Philadelphia and State of Pennsylvania, have invented certain new and useful Improvements in Internal-Combustion Engines; and I do hereby declare the following to be a full, clear, and exact description of the same, reference being had to the accompanying drawings, forming part of this specification, and to the figures and letters of reference marked thereon.

This invention relates to internal combustion engines and more especially to the mechanism for controlling the inlet and discharge of the gases, the objects of the invention being to provide a construction which may be effectively balanced both with respect to the movement of the rotary and other movable parts, and with respect to the pressure exerted on the moving parts during the compression and explosion cycles.

Other objects of the invention are to provide a simple and compact arrangement readily accessible for repair and with which the friction and wear on the valve mechanism will be reduced to a minimum.

Another object of the invention is to provide a valve mechanism embodying a rotary cylindrical valve with packing members for cooperation therewith to prevent leakage, said packing members being held in working contact with the valve by pressure within the cylinder, whereby the employment of springs may be avoided.

Referring to the accompanying drawings,—Figure 1 is a side elevation more or less diagrammatic in character, showing the cylinders and some portions of a four-cylinder engine embodying the present improvements; Fig. 2 is an end elevation with some of the parts illustrated diagrammatically and in dotted lines; Fig. 3 is a detail section in a vertical longitudinal plane through two of the cylinders and through the valve chamber, the valve itself, however, being omitted, together with a packing member over one of the cylinders; Fig. 4 is a detail section in a horizontal plane through the valve and one side of the cylinder head showing the preferred arrangement of intake and exhaust passages and ports; Fig. 5 is a diagrammatic plan showing the arrangement of the ports and chambers in the valve for controlling the admission and ex-

haust to all four of the cylinders; Fig. 6 is a detail section in a vertical plane indicated generally by the line 6—6 of Fig. 3; Fig. 7 is a section corresponding to Fig. 6 taken substantially in the plane indicated by the line 7—7 of Fig. 3; Fig. 8 is a detail section through the valve alone in a plane indicated by the line 8—8 in Fig. 5.

Like letters of reference in the several figures indicate the same parts.

In the engine illustrated and which is of the preferred construction, the cylinders are cast *en bloc*, but of course may be cast in separate units and connected in the usual way.

The cylinder casting is indicated generally in Fig. 1 by the letter A and around the upper ends of the cylinders there is a water jacket enlargement A', as usual. The working chambers of the cylinders are indicated in Figs. 3 and 6 by the reference letter B and from these two figures of the drawing it will be noted that each cylinder at its upper end merges into two outwardly and upwardly extending passages C, said passages being on opposite sides of the median plane of the cylinders and at their upper ends the walls of the passages are provided with inwardly facing ports or passages C'. Said ports or passages C' are located at diametrically opposite points and facing each other, but are spaced apart a distance which will admit of the valve together with the packing members being located directly between them and immediately above the working chambers B of the cylinders. In forming the chamber between the passages C for the reception of the valve and the packing members for cooperation therewith, the head of the casting is preferably divided in a diagonal plane so as to provide connecting flanges D D' which on one side of the engine are below the ports C' and on the opposite side of the engine, above said ports. This construction permits of the convenient formation of a chamber having a central cylindrical portion and side portions which are in the form of longitudinal channels with vertical side walls E and horizontal top and bottom walls E', the division or parting line extending diagonally from the upper corner of one channel and the lower corner of the opposite channel, as best seen in Figs. 6 and 7 of the drawing.

The cylinders are preferably arranged in pairs, the first and second cylinders consti-

tuting one pair and the third and fourth cylinders another pair. Between each pair of cylinders the head of the casting is formed with an intake passage F to which the intake manifold F' is connected. Said passage F extends over the valve chamber and is provided on diametrically opposite sides of said chamber with oppositely disposed ports F² substantially corresponding to the ports C' before referred to. On the outer sides or at the ends of the valve chamber and at a point between the two pairs of cylinders, ports and passages are formed to carry away the burnt products of combustion, said ports and passages being the exhaust ports and passages and are indicated in Fig. 4 by the reference letter G. They communicate with the exhaust manifold G', Fig. 1, for leading the burned gases away to any suitable discharge.

The cylindrical valve indicated generally by the letter H¹ is journaled in bearings I at each end of the head casting and is preferably supported in said bearings with a clearance between the walls of the chamber and the periphery of the valve sufficient to prevent any friction or contact and to permit of such distortion of the valve as will occur through unequal heating. This valve extends throughout the whole length of the head casting and at one end its shaft is provided with a drive wheel I', Fig. 1, preferably a sprocket wheel over which a silent chain, indicated by I², passes from a smaller sprocket wheel, indicated at I³ in Fig. 2, the ratio between these sprocket wheels being four to one, whereby the valve will be rotated one complete revolution in four revolutions of the crank shaft, although it will be understood that with a different arrangement of ports and passages in the valve from that about to be described, the ratio of rotation would be correspondingly changed.

For preventing leakage between the movable and fixed ports packing members are introduced in the valve chamber on diametrically opposite sides of the valve in the rectangular spaces or channels before referred to. These packing members are preferably blocks K rectangular in vertical section parallel with the axis of the valve, but having concave or semi-cylindrical faces k which bear against and form substantially gas tight joints with the periphery of the valve. The packing members are somewhat loosely supported in position in the valve chamber; thus, there is preferably provided a clearance at k' along their top and bottom faces, the supporting bearings being at the outer portions only of the members, as shown at k². Each packing member K is provided in its concave face with an elongated port k³, Fig. 3, and in its rear face with two circular apertures corresponding to similar apertures communicating with the ports or

passages C', F², or G. Said circular apertures are adapted to receive cylindrical packing rings L forming the passages through which the gases flow, as will be readily understood. By providing two cylindrical passages with superposed cylindrical packing rings (herein, not only is the flow of gas not obstructed, but the packing members themselves will be held with a certain degree of freedom and each may adjust 70 itself to conform to any slight irregularities or distortions of the cylindrical valve, such as are liable to be caused by the variations in temperature to which the valve is subjected or by wear. The valve is provided 75 with sets of ports and passages for opening communication between the ports of a set whereby each cylinder will, at the proper time, be first put into communication with the intake passage between the pair of cylinders and then after the compression and 80 explosion strokes will be put into communication with the exhaust passage on the outer side of the pair of cylinders. Each cylinder is put into communication with the proper passage through both of the ports C' simultaneously, thus affording a very free and unobstructed entry and exit for the gases and by reason of the ports and passages, together with the packing members 85 being located on diametrically opposite sides of the valve all pressures are balanced in their effect on the valve and a practically complete and highly effective scavenging and a uniform supply of combustible will 90 be effected. As illustrated in the drawings, the preferred type of valve is built up of a series of sections mounted on a central shaft, the division line between the sections being indicated at h in Fig. 4 and said valve is 95 provided with two diametrically oppositely arranged exhaust ports H' at the ends for the two end cylinders, and with four exhaust ports H², H³, at the center for the two intermediate cylinders, respectively. In a 100 median plane between the cylinders of each pair it is provided with four intake ports H', H⁴, two for each of the respective cylinders of a pair. In the plane of each cylinder the valve is provided with four cylinder 105 ports H⁵, H⁶, the ports H⁵ being adapted to register simultaneously with the oppositely disposed ports in the packing members K for opening communication with the intake ports H⁴ and the ports H⁶ to register simultaneously with the ports in the packing members K for opening communication with the exhaust ports H', H² or H³ as the case may be, all as will be readily understood 110 from the development of the valve illustrated in Fig. 5.

The communicating passages between the ports in the valve are formed by radial walls k⁴, best seen in Figs. 6, 7, and 8, and the outlines of which are shown in the de- 115 120 125 130 135 140 145 150 155 160 165 170 175 180

velopment in Fig. 5, but it will be understood that these ports and passages may be formed in any suitable manner, although it is preferred that the valve should present an unbroken periphery in the plane of the division lines between the packing members so as to avoid any escape of gases between said members.

The head casting containing the valve chamber and passages before described, it will be understood from Figs. 3, 6 and 7, is provided with a water chamber formed as a part of the water jacket and the water may be withdrawn from said chamber at the top through a water circulating connection N and supplied to the lower portion of the water jacket through a tap hole such as is ordinarily employed.

The igniting mechanism, such, for instance, as the dual spark plugs O are preferably located with their terminals in the cylinder passages where they will be effectively cleaned by the gases flowing past the same and will invariably be in a position to ignite a pure portion of the charge which is taken into the cylinder during the inspiration stroke.

In operation, the valve is rotated one half turn during each two revolutions of the crank shaft. It will present the proper ports for opening communication between the intake and both ports of the cylinder simultaneously during the inspiration stroke, all ports will be closed completely during the compression and explosion strokes and both cylinder ports will be opened to the exhaust ports and passages simultaneously during the exhaust stroke. These operations are repeated during the succeeding half turn of the valve, and the order in which the explosions occur is, with the arrangements shown, first in the left hand cylinder of Figs. 3, 4 and 5 then in the third cylinder, then in the fourth cylinder and finally in the second cylinder. In other words, the order is 1, 3, 4, 2 and so on.

The packing members are held up in working contact with the valve by the pressure exerted by the gases tending to pass through them into the valve, and owing to the large area of their contact faces with the valve, the pressure will always be sufficient to maintain a proper engagement, although if so desired, the cylindrical packing ring may be spring rings telescoped or concentrically arranged one within another and slightly tapered so as to exert a tendency to advance the packing members into contact with the valve, as will be readily understood from Fig. 6 of the drawings.

Having thus described my invention, what I claim as new and desire to secure by Letters Patent of the United States, is:

1. In an explosive engine, a rotary cylindrical valve having corresponding inde-

pendent oppositely disposed sets of inlet ports in its cylindrical wall and passages connecting the ports of each set and corresponding independent oppositely disposed sets of exhaust ports in its cylindrical wall and passages connecting the ports of each set, a cylinder having oppositely disposed ports in position to register simultaneously each with one port of the corresponding oppositely disposed ports of each set in the valve and inlet and exhaust passages having ports for registering respectively with the other port of each set and through which motive fluid is conducted to and the burned gases away from the valve.

2. In an explosive engine, the combination with a cylinder having ports arranged diametrically opposite to and facing each other, of a rotary cylindrical valve mounted between the ports on an axis intersecting the axis of the ports, said valve having corresponding independent oppositely disposed sets of inlet ports and passages connecting the ports of each set and corresponding independent oppositely disposed sets of exhaust ports and passages connecting the ports of each set, said cylinder ports and one of the ports of each set of valve ports being in the same vertical plane, and inlet and exhaust passages having ports in position to register respectively with the other ports of the sets and through which motive fluid is conducted to and the burned gases away from the valve.

3. In an explosive engine, the combination with a cylinder having oppositely branching passages at its upper end terminating in oppositely disposed ports facing each other, of a rotary cylindrical valve mounted between ports on an axis at right angles to the axis of the cylinder, said valve having diametrically opposite inlet ports and diametrically opposite exhaust ports for successively establishing communication simultaneously with the said cylinder ports, and independent inlet and exhaust ports in the cylindrical wall of the valve on opposite sides of the first mentioned valve ports but in communication therewith and ported supply and exhaust ducts with which they register successively.

4. In an explosive engine, the combination with a cylinder having oppositely branching passages at its upper ends terminating in diametrically opposite ports facing each other, a valve chamber intermediate said ports with its axis at right angles to the axis of the cylinder, and a water chamber surrounding said valve chamber, of a cylindrical valve mounted in said valve chamber and having diametrically opposite ports for registering simultaneously with the cylinder ports, said valve also having inlet and exhaust ports in its cylindrical wall and in transverse planes on opposite

sides of said first mentioned ports and inlet and exhaust ports and passages through which motive fluid is supplied to and the burned gases conducted away from the valve 5 positioned to periodically register with the last mentioned valve ports.

5. In an explosive engine, the combination with a cylinder having oppositely branching passages terminating in oppositely disposed ports facing each other, and inlet and exhaust passages each having oppositely disposed ports facing each other, said inlet and exhaust ports being located in different planes on opposite sides of the axis of the 10 cylinder, of a rotary cylindrical valve having diametrically opposite ports for registering with the cylinder ports, inlet ports and exhaust ports respectively in the planes of the said passage ports, and independent 15 passages within said valve for establishing communication between the inlet ports on each side of the valve and exhaust ports on each side of the valve.

6. In a multiple cylinder explosive engine, the combination with a plurality of cylinders arranged in a line, side by side, a cylindrical valve chamber located above and with its axis intersecting the axis of all the cylinders, each cylinder having oppositely 20 disposed upwardly extending passages terminating in ports on diametrically opposite sides of the valve chamber, intake passages with diametrically oppositely disposed ports in planes intermediate alternate pairs of 25 cylinders, and exhaust passages having diametrically opposite exhaust ports located in planes on the opposite sides of the cylinders from the inlet ports, of a rotary valve having oppositely disposed inlet ports and 30 oppositely disposed exhaust ports for registering with the cylinder ports simultaneously, and oppositely disposed inlet ports located in the planes of the intake ports for registering 35 with the corresponding ports of the valve chamber and oppositely disposed exhaust ports for registering with the corresponding exhaust ports of the valve chamber, the inlet ports and exhaust ports of the 40 valve for each cylinder being in communication 45 with the corresponding port on the same side of the valve.

7. In an explosive engine, the combination with a cylinder having a port communicating therewith and a rotary cylindrical valve, of a packing block having a port therein for establishing communication between the cylinder port and valve port, and a cylindrical packing ring bridging the joint 50 between the packing block and cylinder head.

8. In an explosive engine, the combination with a cylinder, cylinder head and cylindrical valve chamber in the cylinder head, of a cylindrical valve mounted in said 55 valve chamber, a ported packing block hav-

ing a cylindrical face for coöperation with the valve, and a cylindrical packing ring extending partly into the packing block and partly into the cylinder head, said cylindrical packing ring forming a part of the communicating passage between the cylinder and valve. 70

9. In an explosive engine, the combination with the cylinder and cylinder head having a cylindrical valve chamber therein, 75 with oppositely disposed rectangular enlargements of said valve chamber, and ports and passages through which communication is established between said enlargements and the cylinder, of a cylindrical valve mounted within the valve chamber, rectangular packing blocks mounted in said oppositely disposed enlargements of the valve chamber, and cylindrical packing rings bridging the joints between said packing blocks and cylinder head, said packing rings constituting a part of the communicating passages between the cylinder and valve. 80 85

10. In an explosive engine, the combination with the cylinder, cylinder head having 80 the cylindrical valve chamber therein, and a transverse rectangular enlargement of said valve chamber, of a cylindrical valve located within the chamber, a rectangular packing block in said enlargement and having a concave face for coöperation with the valve, said block being loosely supported in said enlargement of the valve chamber in directions both transversely and longitudinally of the axis of the valve, whereby it may conform to any distortion of the valve, there being coöperating ports and passages in the cylinder head, packing block and valve, respectively. 90 95 100

11. In an explosive engine, the combination with the cylinder, cylinder head having a cylindrical valve chamber therein with a transverse enlargement and a passage for opening communication between the cylinder and said enlargement of the valve chamber, 105 of a cylindrical valve mounted in the valve chamber with a clearance between the periphery of the valve and inner face of the valve chamber whereby contact between them is prevented, and a ported packing block having a cylindrical face for coöperation with the valve, said packing block being mounted in the enlargement of the valve chamber and taking a bearing in said chamber only at its outer edge, whereby it is permitted a limited movement transversely of the valve chamber to accommodate itself to irregularities in the valve face. 110 115 120

12. In an explosive engine, the combination with the cylinder, cylindrical valve 125 chamber having a transverse rectangular enlargement with a port therein in communication with the cylinder, of a cylindrical valve mounted in the valve chamber with a clearance between the periphery of the valve 130 135

and walls of the valve chamber whereby contact between them is prevented, a ported rectangular packing block mounted in the enlargement of the valve chamber and having a concave face for coöperation with the valve, said block being supported in the valve chamber solely by bearings remote from the face of the valve, whereby a clearance is provided around said block to permit of the block being moved transversely with respect to the valve to accommodate irregularities in the valve face.

13. In an explosive engine, the combination with the cylinder, cylindrical valve chamber, and cylindrical valve, of a ported packing block having a cylindrical face for coöperation with the valve, and an outwardly expandable cylindrical packing ring extending partly into the packing block, and partly into the cylinder casting, whereby leakage between the cylinder casting and block is prevented.

14. In an explosive engine, the combination with a cylinder and a cylindrical valve having a port in its cylindrical wall, of a packing member bearing against the cylindrical outer face of the valve, said packing member having a passage therethrough and an outwardly expandable packing ring bridging the joint between said packing member and cylinder and forming a part of the communicating passage between the cylinder and valve.

15. In an explosive engine, the combination with a cylinder, a cylindrical valve having a port in its cylindrical face, and a ported packing block bearing against the

cylindrical face of the valve, of an outwardly expandable packing ring forming a communicating passage between the port in the packing block and cylinder, said ring having a frusto conical outer surface for advancing the packing block and bridging the joint between said packing block and cylinder casting.

16. In an explosive engine, the combination with a cylinder, a cylindrical valve having a port in its cylindrical face and packing block for coöperation with the cylindrical face of the valve and having an elongated port therein, of a plurality of cylindrical packing rings arranged side-by-side to form parts of the communicating passageway between the said port and cylinder, said packing rings extending partly into the block and partly into the cylinder casting, whereby leakage between the block and cylinder casting is prevented.

17. In an internal combustion engine the combination with the cylinder, cylinder head having a cylindrical valve chamber therein and transverse rectangular enlargements of said chamber, said head being formed in sections with the lines of separation extending from diagonally opposite corners of the rectangular enlargements, of a cylindrical valve journaled in the chamber and packing blocks confined in the rectangular enlargements of the chamber.
